UNITED STATES PATENT OFFICE.

JOSEPH ZANALETTI, OF CHICAGO, ILLINOIS.

AVIATION-MOTOR.

1,323,803.

Specification of Letters Patent.

Patented Dec. 2, 1919.

Application filed November 19, 1917. Serial No. 202,851.

To all whom it may concern:

Be it known that I, JOSEPH ZANALETTI, a subject of the King of Italy, and resident of Chicago, in the county of Cook and State of Illinois, have invented a certain new and useful Improvement in Aviation-Motors, of which the following is a specification.

This invention relates to improvements in motors and particularly in internal combustion engines for use in aviation, and has reference especially to the valve operating and actuating mechanism for such engines.

The principal object of this invention is the provision of simplified means for eliminating the usual valve shaft and connecting gears for operating or actuating the valves and also the provision of a construction which is of extreme lightness and of maximum simplicity of construction and operation.

A further object of this invention is the provision of a cam element on the crank shaft, this cam element having means for actuating the push rods for a part of its rotation, the push rods remaining in their neutral or non-actuated position during the remainder of the revolution of the cam element and also during the next succeeding revolution thereof.

Further objects of this invention include improvements in details of construction and arrangement, as will more fully hereinafter appear.

To the accomplishment of the foregoing and such other objects as may hereinafter appear, my invention consists in the construction, combination and arrangement of parts hereinafter described and sought to be defined in the appended claim, reference being made to the accompanying drawing forming a part hereof and which shows, merely for the purpose of illustrative disclosure, a preferred embodiment of my invention, it being expressly understood however that various changes may be made in practice within the scope of the claim, without digressing from my inventive idea.

In the drawings:—

Figure 1 represents a view in side elevation of the operating mechanism for actuating the push rods and valves, together with a casing containing the mechanism.

Fig. 2 is a vertical transverse section taken substantially on line 2—2 of Fig. 1.

Fig. 3 is a side elevation of one of the

side plates for holding the rollers on the track.

In both the views the same reference characters are employed to indicate similar parts.

I have shown this invention embodied in a rotary engine in which the crank case and the plurality of radiating cylinders turn on the crank shaft, the latter remaining stationary, but it is expressly to be understood that it is readily adapted for use in connection with motors of other types of construction.

The numeral 1 designates the crank shaft of the motor, having the crank 2 to which the connecting rods of the cylinder are connected, as is well understood. This crank shaft is stationary, and mounted for rotation thereon is the casing 3 of the form shown, adapted to be secured to a suitable part of the motor casing, with which it rotates.

Secured to this crank shaft 1 is the cam element 4, which as shown, is of cylindrical form, and provided with a plurality of tracks, parts of which are arranged at different elevations, for actuating the push rods, as will presently be described. The outer track 1 I designate by the reference character 5, the inner track being designated 6 by the reference character 6. It is to be noted from a consideration of Fig. 2 that I arrange these tracks in pairs, on each side of the outer surface of the cam element 4. These tracks are raised to provide cams 9 and grooves 7 on each side thereof. I also provide means whereby elements engaging one of the tracks 5 may slip over to one of the tracks 6 and vice versa, this means taking the form of the diamond shape cross 8, the elongated points of which extend a considerable distance into the grooves 7 between the elongated points of the ends of the tracks 5 and 6, as clearly shown to the left in Fig. 2. In connection with these tracks 5, it is to be noted that they are provided with the cam portion 9, which is raised a considerable distance above the normal level thereof and above the normal level of the track 6, and also that these high cam surfaces on the two track members 5 are located on opposite sides of the cam element, as clearly shown in Fig. 1. Not only that, but the cross over elements 8, between the respective pairs of tracks 5 and 6, are

located on opposite diametric sides of the cam element, the one for the pair of tracks to the left in Fig. 2 being shown in full lines and the one for the pair of tracks 5 to the right being to the rear of the cam element and therefore shown in dotted lines.

The push rods 10 may be arranged in pairs, as shown, and are connected to the valves, as is well understood. These push rods are slidably mounted within the casing and each has its end provided with the relatively wide yoke or pronged bifurcation 11 in which is mounted a pin or shaft 12. Slidably mounted on this pin or shaft 12 15 is the cam engaging element 13, which preferably takes the form of a roller, as shown, and engages the top surfaces of the tracks 5 and 6. In order to prevent this roller from becoming disengaged from the tracks, I provide the side plates 14 which are held together by rivets 14' and are of greater length than the radial width of the roller and have their lower edges formed to loosely fit within the grooves 7. The upper parts 20 of these plates are cut away as at 15 so as to permit an axial movement of the roller 13 and plates 14 on the shaft 12.

As stated before, the rollers 13 engage the top surface of the tracks 5 and 6, the 30 side plates 14 fitting within the grooves. As the casing 3 turns about the crank shaft 1, the rollers will be guided into engagement with the high cam part of track 5 and then by means of the cross over into engagement 35 with the track 6 and after completely traversing the track 6 will be guided back again into the low part of track 5 and subsequently onto the high cam part thereof. It is during its travel from the low to the 40 high part of track 5 that the push rod is moved upwardly so as to actuate its valve and as the high part of track 5 extends for half the circumference of the cam element it is seen that the valve is open for one-half 45 of one revolution and that as the roller, con-

nected to the push rod is in engagement with a lower surface during the remainder of that revolution and also for the complete succeeding revolution, the valve remains closed, each valve being operated for a 50 period of time corresponding to a suitable part of revolution during each two revolutions of the casing about the crank shaft.

It is therefore seen that I have provided a very simple construction whereby the 55 valve operating mechanism is operated directly from the crank shaft without the use of gears or complicated structures of any kind. The construction is extremely light, simple, readily adjusted and will not get out 60 of order.

Having described my invention, what I claim is:

An internal combustion engine including in combination, a stationary crank shaft; a 65 cam element secured thereto, said cam element being provided with a plurality of tracks, said tracks being arranged in pairs, one of the tracks of each pair having a radially raised portion for part of the circumference thereof, the remainder of said track and the companion track being lower than said raised portion and of substantially uniform level; grooves provided on each side of said track and cross over constructions provided between said tracks in said cam elements; a casing mounted for rotation relative to said crank shaft; push rod elements slidably mounted in said casing; rollers movably mounted on the inner ends 80 of said push rod elements and engaging said tracks, members associated with said rollers to fit said grooves whereby said push rods are moved to one position for substantially half a revolution of said casing and are moved to another position for substantially one and one-half revolutions of said casing. 85

J. ZANALETTI.
